Inventor,

Samuel J. Shimer
By his Attorney, A. G. Heylman.

UNITED STATES PATENT OFFICE.

SAMUEL J. SHIMER, OF MILTON, PENNSYLVANIA, ASSIGNOR TO SAMUEL J. SHIMER & SONS, OF SAME PLACE.

TOOL-HOLDER FOR CUTTER-HEADS.

SPECIFICATION forming part of Letters Patent No. 387,924, dated August 14, 1888.

Application filed December 14, 1887. Serial No. 257,844. (No model.)

To all whom it may concern:

Be it known that I, SAMUEL J. SHIMER, a citizen of the United States of America, residing at Milton, in the county of Northumberland and State of Pennsylvania, have invented 5 a new and useful Tool-Holder for Cutter-Heads, of which the following is a specification.

My invention has relation to improvements in tool-holders for cutter-heads; and the object 10 is to provide a tool-holder of the kind named, which is easily adjusted to the head, readily secured thereto, and conveniently adjusted therein and removed therefrom.

My invention is particularly applicable to 15 secure beading-tools to the head; and it consists in the novel construction and combination of parts, as will be hereinafter fully specified, and specially pointed out in the claims made thereto.

20 In the accompanying drawings I have fully illustrated my invention, wherein Figure 1 is a side view of a cutter-head with my improved tool-holder applied and a beading-tool clamped in position. Fig. 2 is a view of the beading- 25 tool. Fig. 3 is a view of the section of the clamp of the tool-holder which fits in the slot of the cutter-head. Fig. 4 is a view of the clamping-plate. Fig. 5 is a view of the clamping-screw, shown bottom face up. Fig. 6 is a 30 perspective view of the parts assembled detached from the cutter-head. Fig. 7 is a transverse sectional view taken on the line X X of Fig. 1.

Reference being had to the drawings, A designates a cutter-head having a hole, 1, to receive a vertical spindle, and is formed with 35 T-shaped slots *b* in its respective faces to receive the body-section of the clamping devices. I have shown the cutter-head as being 40 of the pattern and style of that shown and described in my Letters Patent of the United States of America, No. 319,933, dated June 9, 1885; but it will be perceived that the tool-clamping means may with equal adaptability be used with any cutter-head having T-shaped 45 slots to take the body-section of the clamp.

B designates the body-section of the tool-holding device. This consists of a piece of metal shaped with side flanges, 2, to engage in 50 the grooves *c* of the slot of the head, and a

stem or body part, 3, to fit in the stem of the T-shaped slot *b* of the cutter-head. At one end of the body-section, on the outer face, is formed a flange or jaw, 4, which has its ends extended, as at 5, to set over and on the face of the cutter-head adjacent to the slots therein, and is dovetailed to receive the dovetail flange of the tool, as at 6. At the other end of the face of the body-section is a flange, 7, having its ends extended to set over and on the face of the cutter-head, as at *d*, and having its lower or inner face flared off for the clamping-plate to set against, as at 8. At a proper location in the stem of the body part is a threaded hole, 9, to take the threaded clamping-bolt. 55

C designates the clamping-plate, which is formed with flaring edges 10 11, the upper one of which sets on the flared edge of the flange 7 and the lower one rests on the flange of the tool in the cutter-head. The ends of the clamping-plate are extended to reach over and set on the adjacent faces of the cutter-head and give clamping-surface to the plate. The clamping-plate is made to set a little flush in its bed, so as to give more pinch when screwed down 60 on the knife or tool. In the clamping-plate is a plane bolt-hole, 12, made somewhat elongated in order that the clamping-plate may automatically assume the proper position when the clamping-bolt *a* is applied, or when a tool 65 of different width from an old one is used. The clamping-bolt *a* has a threaded stem and engages the threads in the body-section, and is of such length that it can be screwed down 70 with the under face of its head on the clamping-plate. 75

D designates the beading-tool, having its cutting end shaped to make the desired bead in the stock, and formed with flaring base-flanges 13, to set in the dovetail groove formed 80 by the jaw on the body part of the clamp and the inner edge of the clamping-plate, as shown in Figs. 1 and 6 of the drawings. 85

The parts are assembled as follows: The section B is arranged in the slot of the head, then 90 the tool is laid on the dovetail flange, the clamping-plate arranged in position, and the clamping-screw inserted and screwed down. The parts are then in operative aggroupment.

If at any time it is desired to change the 95

tools or to set them to a certain cut, the clamping-screw may be loosened and the tool removed or the adjustment made.

What I claim is—

- 5 1. The tool-holder herein described, consisting of the body-section B, formed with a stem, 3, having side flanges, 2, to set in a T-shaped slot, an outer projecting dovetailed jaw, 4, on one end, a projecting flange, 7, on the other end, and a threaded bolt-hole, 9, the clamping-plate 6, formed with flaring edges 10 11, to set flush in its bed formed by the jaw 4 and flange 7, and an elongated bolt-hole, 12, and the clamping-screw a, projected through the clamping-plate into the threaded hole of the stem to force the clamping-plate on the bit and under the jaw, substantially as described.
- 15 2. The combination, with a cutter - head

formed with T-shaped slots in its faces, of an adjustable tool-holder consisting of a body-section, B, having a stem with side flanges to fit the T-shaped slots of the cutter-head, and having a projecting clamping-jaw, 4, on one end and a projecting flange, 7, on the other end, and a threaded bolt-hole, 9, through its stem, 25 a clamping-plate, 6, formed with flaring edges, and an elongated bolt-hole, 12, a clamping-screw, a, to hold the parts together, and a cutter-tool between the jaw of the part B and the clamping-plate, substantially as described. 30

In witness whereof I have hereunto set my hand in the presence of two attesting witnesses.

SAMUEL J. SHIMER.
